CLAIM

The ornamental design for an end cap for automobile differential, substantially as shown and described.

DESCRIPTION

FIG. 1 is a perspective view of an end cap for automobile differential showing my new design;

FIG. 2 is a front elevational view thereof;

FIG. 3 is a right side elevational view thereof;

FIG. 4 is a left side elevational view thereof;

FIG. 5 is a bottom plan view thereof.

The rear thereof comprises a flat-surfaced, peripheral bolt flange surrounding a cavity, all without ornamentation.
